Primary Examiner — Bao-Yen T Nguyen*Assistant Examiner* — Emily Anna Saunders(74) Attorney, Agent, or Firm — Dunlap Bennett & Ludwig, PLLC(57) CLAIM

The ornamental design for a game board, as shown and described.

DESCRIPTION

The sole FIGURE is a top plan view of a game board, showing my new design.

The broken lines show portions of the game board that form no part of the claimed design.

The game board is of conventional thickness that forms no part of the claimed design. The rear and sides of the game board form no part of the claimed design.

1 Claim, 1 Drawing Sheet(56)
